DESIGN FOR A VANITY CASE

Robert T. Plate, Grosse Pointe Park, Mich.

Application February 7, 1945, Serial No. 117,805

Term of patent 14 years

(Cl. D86—10)

To all whom it may concern:

Be it known that I, Robert T. Plate, a citizen of the United States of America, residing at Grosse Pointe Park, in the county of Wayne and State of Michigan, have invented a new, original, and ornamental Design for a Vanity Case, of which the following is a specification, reference being had to the accompanying drawing, forming a part thereof, in which Figure 1 is a rear elevation of a compact embodying my new design; Figure 2 is a front elevation of the vanity case shown in Figure 1; and Figure 3 is a side elevation of the vanity case shown in Figure 1.

I claim:

The ornamental design for a vanity case, substantially as shown.

ROBERT T. PLATE.
